PREPARATION OF LIQUID ALKYLATED PENTABORANE-9

George E. Ryschkewitsch, Columbus, Ohio, assignor, by mesne assignments, to Olin Mathieson Chemical Corporation, a corporation of Virginia

No Drawing. Filed Dec. 1, 1955, Ser. No. 550,302

10 Claims. (Cl. 260—606.5)

My invention relates to the manufacture of alkylated pentaboranes and, in particular, to the alkylation of pentaborane-9 with monoolefin hydrocarbons while the reactants are in admixture with tetrahydrofuran, a lower monoalkylated tetrahydrofuran or a mixture thereof. The products produced in accordance with the method of my invention can be used as fuels when burned with air, as described in the application of Chiras and Mezey, Serial No. 501,742, filed April 15, 1955.

It is known in the art to prepare pentaborane, which is a relatively stable, colorless liquid melting at -46.8° C. Pentaborane is a boron hydride or borane, and the art is aware that the burning of a borane with oxygen liberates considerably more energy than the oxidation of a corresponding amount of hydrocarbon, producing very high flame temperatures. This suggests the use of pentaborane as a fuel of very high energy content. Pentaborane suffers from the disadvantage, among other things, however, that it has a relatively high vapor pressure, its vapor pressure being 66 mm. of mercury at 0° C. and its boiling point at atmospheric pressure being 58° C.

One of the objects of my invention is to provide a method for producing liquid alkylated pentaboranes which are less volatile and less toxic than pentaborane-9 but at the same time approaching pentaborane-9 insofar as heat of combustion is concerned. Thus, in accordance with my invention, I have discovered that pentaborane-9 can be reacted with monoolefin hydrocarbons containing from 2 to 5 carbon atoms while in admixture with tetrahydrofuran, lower monoalkylated tetrahydrofurans or mixtures thereof to provide alkylated pentaboranes which are stable, relatively non-volatile liquids with convenient handling characteristics. By this process, monoolefin hydrocarbons which are available at rather low cost and large tonnages can be reacted with pentaborane-9 to form valuable alkylated pentaboranes in yields which are substantially greater than those which are obtained when the olefins and pentaborane are reacted not in admixture with the tetrahydrofuran or alkylated tetrahydrofuran.

The exact manner of the action of tetrahydrofuran or alkylated tetrahydrofuran in increasing the yield of the alkylation reaction is not known to me. Thus, they may be acting as a solvent or as a solvent and catalyst. It has been shown, however, that substantial increases in the yield of alkylated products can be obtained when pentaborane-9 is alkylated with the olefin in the presence of the tetrahydrofuran or alkylated tetrahydrofuran, in comparison with the yield obtained when the pentaborane-9 is alkylated with the olefin but without tetrahydrofuran or alkylated tetrahydrofuran.

The following example illustrates an embodiment falling within the scope of my invention and is to be considered not limitative. In the example, the term "millimoles" signifies milligram moles.

Example

In this experiment 10.00 millimoles of pentaborane-9

2

mersed in a Dewar flask filled with liquid nitrogen (temperature -196° C.). Then 10.7 millimoles of tetrahydrofuran, followed by 9.92 millimoles of isobutene, were condensed in the bulb at the same temperature.

5 At this temperature the reactants were solids. The bulb was sealed, removed from the cooling flask, allowed to warm to room temperature and then heated for $7\frac{1}{2}$ hours at 150° C. in a Fisher Isotemp oven. After being removed from the oven the bulb was allowed to cool 10 to room temperature and then attached to a vacuum line. In the next step it was cooled with liquid nitrogen and opened to the vacuum line.

A part of the crude product in the bulb was allowed to warm up and was fractionated through a series of 15 cold traps. In the first instance the material was allowed to pass through three traps, the first being held at -78° C., the second at -116° C., and the third at -196° C. Through a series of additional fractionation operations, carried out with cold traps, unreacted pentaborane-9 20 and the tetrahydrofuran were finally isolated in a -78° C. trap and the hydrocarbon fraction in a -196° C. trap. Assuming that the tetrahydrofuran was not used up during the reaction, the quantity of pentaborane-9 in the trap was determined by the difference. The hydrocarbon fraction was analyzed for olefin by conventional gas analysis, and was found to contain 0.37 millimole of isobutane and 1.41 millimoles of isobutene.

The remaining material in the bulb was fractionated 25 through a series of four cold traps held at -8° C., -18° C., -52° C. and -78° C., respectively. In the trap held at -52° C. a fraction was obtained which exhibited a vapor pressure of 4.4 mm. at 26.5° C. temperature. This material was refractionated through three 30 traps held at -8° C., -18° C., and -52° C., respectively, and in the -52° C. trap there was collected a product which had a vapor pressure of 5 mm. at 24° C.; this vapor pressure corresponds closely with the vapor pressure of ter-butylpentaborane. The weight of isobutylpentaborane was 60.7 percent based on the pentaborane used in the reaction. Some of the pentaborane-9 consumed was transformed into tri-iso-butylborane and other viscous liquids containing carbon which are not volatile at room temperature. The amount of tri-iso-butylborane formed in the reaction was 1.18 millimoles. 35 40 45 A controlled run in which tetrahydrofuran was not present was also completed, and a comparison of the results obtained in this run with the run in which tetrahydrofuran was present is given in Table I below:

Table I

	Control	Example I
Reactants (m. moles):		
B_5H_9	10.00	10.00
$i-C_4H_9$	9.32	9.98
tetrahydrofuran		10.70
Products (m. moles):		
$B_5H_9C_4H_9$	Trace	1.39
$B(C_4H_9)_3$	None observed	1.18
C_4H_{10}	0.0	.37
H_2	Trace	Trace
Reactants consumed (percent):		
B_5H_9	0.44	22.9 ¹
$i-C_4H_9$	0.65	86.1
Remarks	Only gas phase present.	Liquid phase present at all times.

65 ¹ B_5H_9 was recovered in a mixture with tetrahydrofuran. B_5H_9 consumption calculated by assuming no change in the amount of tetrahydrofuran had occurred during the reaction.

Various modifications can be made in the procedures 70 of the specific example to provide other embodiments which fall within the scope of my invention. Thus, in place of the isobutylene utilized, there can be substituted other monoolefin hydrocarbons having from 2 to 5 car-

bon atoms, for example, ethylene, propylene, 1-butene, 2-butene and the like, as well as mixtures thereof. Also in place of the tetrahydrofuran there can be substituted other lower monoalkylated tetrahydrofurans, particularly those not containing more than four carbon atoms, in the alkyl radical, for example, 2-methyl-tetrahydrofuran, 2-ethyl-tetrahydrofuran and the like, as well as mixtures thereof.

In general, the reaction temperature employed will be within the range from about 130° C. to about 190° C., although somewhat higher as well as somewhat lower reaction temperatures can be used. In like manner, the reaction time can be varied widely, generally being within the range from about 1 to about 24 hours and preferably within the range from about 4 to about 8 hours. The ratio of olefin to pentaborane-9 utilized in carrying out my process can be varied widely, generally being within the range from 0.1 to 10 moles of olefin per mole of pentaborane-9. The preferred range of olefin to pentaborane-9 employed is from 0.5 to 2.0 moles of olefin to 1 mole of pentaborane-9, depending upon the degree of alkylation desired. The quantity of tetrahydrofuran or monoalkylated tetrahydrofuran used will generally vary from about 1 to 5 moles per mole of pentaborane-9.

I claim:

1. A method for the preparation of a liquid reaction product of pentaborane-9 and a monoolefin hydrocarbon having from 2 to 5 carbon atoms which comprises reacting from 0.1 to 10 moles of the monoolefin hydrocarbon per mole of the pentaborane-9 at a temperature within the range from 130° to 190° C. while the reactants are in admixture with from 1 to 5 moles, per mole of pentaborane-9, of at least one material selected from the group

consisting of tetrahydrofuran and lower monoalkylated tetrahydrofurans.

2. The method of claim 1 wherein said monoolefin hydrocarbon is ethylene.

3. The method of claim 1 wherein said monoolefin hydrocarbon is isobutylene.

4. The method of claim 1 wherein said monoolefin hydrocarbon is propylene.

5. The method of claim 1 wherein said material is tetrahydrofuran.

6. A method for the preparation of a liquid reaction product of pentaborane-9 and a monoolefin hydrocarbon having from 2 to 5 carbon atoms which comprises reacting from 0.5 to 2 moles of said monoolefin hydrocarbon per one mole of pentaborane-9 at a temperature within the range from 130 to 190° C. while the reactants are in admixture with from 1 to 5 moles, per mole of pentaborane-9, of at least one material selected from the group consisting of tetrahydrofuran and lower monoalkylated tetrahydrofurans.

7. The method of claim 6 wherein said monoolefin hydrocarbon is ethylene.

8. The method of claim 6 wherein said monoolefin hydrocarbon is isobutylene.

9. The method of claim 6 wherein said monoolefin hydrocarbon is propylene.

10. The method of claim 6 wherein said material is tetrahydrofuran.
